BUILDING STRUCTURE

Frank E. McCabe, Shaker Heights, Ohio, assignor to The Grabler Manufacturing Company, Cleveland, Ohio, a corporation of Ohio

Application June 7, 1935, Serial No. 25,459
Renewed January 28, 1937

6 Claims. (Cl. 189—85)

This invention relates to building structures, and more particularly to face-work building structures, and has for an object the provision of new and improved structures of this character.

5 In the drawing accompanying this specification and forming a part of this application, I have shown, for purposes of illustration, embodiments which my invention may assume, and in the drawing:

10 Figure 1 is a fragmentary perspective view of a building structure, embodying the invention, and disclosing parts of the same in horizontal section, and also disclosing parts broken away to more clearly illustrate the construction.

15 Figure 2 is an enlarged fragmentary horizontal sectional view of the securing means, corresponding substantially to the line 2—2 of Figure 1, and showing fastening elements adapted to cooperate therewith,

20 Figure 3 is a view similar to Figure 2, corresponding substantially to the line 3—3 of Figure 1,

Figure 4 is an enlarged fragmentary horizontal sectional view corresponding substantially to the line 4—4 of Figure 1,

25 Figure 5 is a detailed perspective view of clamping means employed in connection with the invention,

Figure 6 is a fragmentary perspective view, similar to Figure 1, and disclosing a different embodiment of the invention, while

Figure 7 is a fragmentary, horizontal sectional view, similar to Figure 3, of the construction disclosed in Figure 6.

30 As shown in Figures 1 through 5 of the drawing, the invention comprises a building structure, wherein a plurality of facing panels 10 are disposed edge to edge and flatwise along the surface of a supporting wall 11, which may be the front wall of a building or the like, and said panels 10 are secured in position along said wall by a plurality of sets of securing means, each set being indicated generally by the reference character 12, and adapted to be positioned between juxtaposed edges of each pair of panels 10; the sets 12 are duplicates in construction and operation and only one of the same will be described in detail.

35 Each of the sets 12 comprises an elongated member 13, preferably of sheet metal, channel-shaped in cross-section, having an intermediate portion 14, angularly extending webs 15 and 16 along opposite edges, and out-turned marginal flanges 17 adapted to rest against the supporting wall 11. Each of the flanges 17 has a plurality 40 of laterally extending, outwardly opening notches

18 in its edge, the notches preferably being formed at regular intervals along the length of each flange 17, and fairly close together. Adapted for accommodation in selected notches 18, are anchoring members 19, each comprising a screw-bolt 20 having a head bearing against the outer face of the related flange 17, and a shank threaded into a wedge part 21. The wedge part 21 is encased in an expansible sleeve 22, which may be of lead, and the wedge part 21 and sleeve 22 10 may be accommodated in a suitable cavity 23 formed in the supporting wall 11. Rotation of the bolt 20 serves to draw the wedge part 21 inwardly and to expand the sleeve 22 into anchoring engagement with the wall of the cavity 23. 15 As many of the anchoring members 19 may be employed as are desired or are necessary, and these may be positioned along the length of the flanges 17, in any selected notches 18, as seems most convenient, a preferable arrangement being shown in the drawing, wherein the anchoring members 19 are positioned in staggered relation along opposite flanges 17 of the member 13. 20 When all of the anchoring members 19 have been tightened, the member 13 is fixedly secured to the supporting wall 11 with the intermediate portion 14 thereof spaced outwardly from the wall 11. 25

30 The intermediate portion 14 of each of the members 13 is provided with a plurality of vertically spaced, transversely extending, parallel slots 24, one end of each slot opening into a longitudinally extending cut-out 25 formed in the web 15 of the member 13, and the opposite end of the slot opening into a similar cut-out 26 formed in the web 16 of the member 13, the slots 35 being formed fairly close together along the length of the intermediate portion 14, and each being adapted to accommodate one of the fastening means 27, it being contemplated that relatively few of the fastening means 27, as compared to the number of slots 24 provided, will be employed, but each may be accommodated in any slot 24 convenient to the location at which it is desired or convenient to place the fastening means 27. 40

45 Each fastening means 27 comprises a connecting member 28, which may be in the form of an oblong piece of suitable metal, adapted for end-wise insertion from either side of the member 13 through the cut-outs 25 and 26, to a position beneath the intermediate portion 14, the connecting member 28 being wider than the slots 24, and having a centrally disposed opening 29 threaded for the reception of the barrel 30 of an actuating screw 31, the barrel 30 of the screw 31, 50 55

outwardly of the intermediate portion 14, carrying a clamping element 32 against which the head 33 of the screw 31 is adapted to bear. The clamping element 32 comprises an oblong metallic plate preferably curved longitudinally, and along each longitudinal edge has formed a laterally extending lug 34, the lugs 34 being provided for a purpose presently to appear.

Each of the sets of securing means is adapted to secure juxtaposed edges of a pair of the panels 10 to the supporting wall 11. The panels 10 are formed for cooperation with the securing means, each of the panels 10 comprising a channel-shaped formation having an intermediate portion 35, angular webs 36 and 37 extending along opposite edges of the portion 35, the web 36 having an inturned marginal flange 38, and the web 37 having an inturned marginal flange 39, both adapted to rest against the outer surface of the portion 14. Each of the angular webs 36 and 37 of the adjoining panels 10, at intervals, is provided with longitudinally extending slots 40 and 41, adapted for the reception of the ends of the clamping members 32, the slots 40 and 41 being sufficiently long to facilitate engagement of the clamping members 32 with the slots, and when the securing screws 31 are taken up, the clamping members 32 are drawn into clamping engagement with the panels 10, the lugs 34 of the clamping members 32 being adapted to abut the adjacent webs of the panels 10 to prevent turning of the clamping members when the screws 31 are rotated.

Installation of the face-work structure is preferably effected by first securing a plurality of the members 13 vertically, and in spaced relation, along the supporting wall 11, through the medium of the anchoring members 19, the members 13 being spaced apart a distance corresponding to the width of the panels it is desired to use. A suitable number of the fastening means, (each including the connecting member 28, the screw 31, threaded into the connecting member 28, and carrying a clamping member 32) are interengaged with the securing member 13 by inserting the connecting member 28, from either side of the member 13, through the cut-outs 25 and 26, and the screw 31 carrying the clamping member 32 at the outer side of the intermediate portion 14, is pushed along the slot 24 toward a central position. As many of the fastening means are employed as desired, and placed in selected slots 24 in the manner referred to, after which the panels 10 are brought into position, and the ends of the clamping members 32 inserted into the slots 40 and 41 of adjacent panels 10, the curved formation of each clamping member 32 being provided to enable the clamping member 32 to clear any raised portions bordering the inner edges of the slots 40 and 41, which might be present as a result of slight inaccuracy in forming the slots 40 and 41, and permit the clamping members 32 to bear directly upon the flanges 38 and 39 of the panels 10, without any tendency to tip or distort the panels 10. The screws 31 are then rotated to bring about clamping engagement of the clamping members 32 with the panels 10. After all of the clamping members 32 have been adjusted, the space between the webs 36 and 37 of the secured panels 10, may be filled with a suitable filling material, indicated at 42.

Although the securing members 13 are shown as secured vertically to the wall 11, it will be understood that these securing members 13 may be arranged horizontally, and the panels 10 secured thereto, or, if desired, the securing mem-

bers 13 may be arranged both vertically and horizontally to present rectangular formations to which all four edges of the panels 10 may be secured, the panels 10 in this latter case of course having all four edges formed as heretofore described to cooperate with the securing means. 5

Referring to Figures 6 and 7, a somewhat different embodiment of the invention is disclosed, comprising elongated securing members 43, each having an intermediate portion 44, webs 45—46, 10 and flanges 47, corresponding to the parts 14, 15, 16, and 17, respectively, heretofore described, the flanges 47 being notched, as at 48 for the reception of anchoring members 49, similar to the anchoring members 19, already described, which fix 15 the securing member 43 to the wall 50.

In this construction, however, instead of employing slots like the slots 24, having entrance at either side of the member 13, each member 43 has only one web, web 46, as shown, provided 20 with a cut-out 51, communicating with a transversely extending slot 52 which terminates short of the opposite web 45, a plurality of similar slots 52 being provided along the length of the member 43 as will be understood. The slots 52 are 25 each adapted to accommodate fastening means including a connecting member 53, having a threaded opening for the reception of a screw 54 like the screw 31, the screw 54 carrying a clamping member 55 like the clamping member 32. 30 Panels 56 formed like the panels 10 are provided and secured by the clamping means to the members 13 in the manner already described; filling material 57 being employed to fill the space between the adjoining panel edges. 35

It will be apparent to those skilled in the art that I have accomplished at least the principal object of my invention, and it also will be apparent to those skilled in the art that the embodiments herein described may be variously 40 changed and modified, without departing from the spirit of the invention, and that the invention is capable of uses and has advantages not herein specifically described; hence it will be appreciated that the herein disclosed embodiments are 45 illustrative only, and that my invention is not limited thereto.

I claim:

1. A building structure of the character described, comprising: a support; securing means fixedly connected to said support, having a pair of spaced walls extending outwardly from said support, and a wall connecting the outer ends of said spaced walls, said spaced walls having aligned cut-out portions for the reception of holding means, and said connecting wall having a slot therein communicating with said cut-outs; a facing member adapted to be secured to said securing means; and holding means insertible through either of said cut-out portions, and adapted to bear on said securing means, said holding means having means extending outwardly through said slot, and having means engageable with said facing member to secure the same to said securing means. 55

2. A building structure of the character described, comprising: a support; elongated securing means fixedly connected to said support, having a wall extending outwardly from said support, and a connected wall spaced from said support and extending substantially parallel to said support, said outwardly extending wall having a cut-out portion therein, and said substantially parallel wall having a transversely extending slot therein communicating with said cut-out; a fac- 75

ing member adapted to be secured outwardly of said securing means; a connecting member insertible through said cut-out into bearing relation with said securing means; a screw threaded into 5 said connecting member and extending outwardly through said slot; and clamping means carried by said screw, and engageable with said facing member to secure the same to said securing means when said screw is tightened.

10 3. A building structure of the character described, comprising: a support; securing means fixedly connected to said support, having a pair of spaced walls extending outwardly from said support, and a wall connecting the outer ends of 15 said spaced walls, said outwardly extending walls having aligned cut-outs therein, and said connecting wall having a slot communicating with said cut-outs; a facing member adapted to be secured to said securing means; a connecting 20 member insertible through the cut-out in either of said spaced walls, into bearing relation with said securing means; a screw threaded into said connecting member and extending outwardly through said slot; and clamping means carried 25 by said screw, and engageable with said facing member to secure the same to said securing means, when said screw is tightened.

4. A building structure of the character described, comprising: a support; elongated securing means fixedly connected to said support, having a pair of spaced walls extending outwardly from said support, and a wall connecting the outer ends of said spaced walls, said spaced walls having aligned cut-outs, and said connecting wall 30 having a slot therein communicating with said cut-outs; a facing member adapted to be secured to said securing means; a connecting member insertible transversely of said securing means, through said cut-outs and into bearing relation 35 with said securing means; a screw threaded into said connecting member, having its shank extending outwardly through said slot, and provided 40

with a head; and clamping means carried by said screw, inwardly of the screw-head, and engageable with said facing member to secure the same to said securing means, when said screw is tightened.

5. A building structure of the character described, comprising: a support; securing means fixedly connected to said support, having a pair of walls extending outwardly from said support, and a connecting wall connecting said pair of walls, and spaced from said support, each of said pair of walls having a cut-out portion for the reception of holding means, and said connecting wall having a slot therein communicating with said cut-outs; a facing member adapted to 15 be secured to said securing means; and holding means insertible through either of said cut-out portions and adapted to bear on said securing means, having means extending outwardly through said slot, and having means engageable 20 with said facing member to secure the same to said securing means.

6. A building structure of the character described, comprising: a support; securing means fixedly connected to said support, having a wall 25 extending outwardly from said support, and a connected wall spaced from said support and extending substantially parallel to said support, said outwardly extending wall having a cut-out portion for the reception of holding means, and 30 said substantially parallel wall having a slot therein communicating with said cut-out; a facing member adapted to be secured to said securing means; and holding means including a connecting member, insertible through said cut-out portion 35 and adapted to bear on said securing means, having threaded means threaded thereto, and extending outwardly through said slot, and said threaded means having abutment means engageable with said facing member to secure the 40 same to said securing means.

FRANK E. McCABE.
